UNITED STATES PATENT OFFICE.

JOHN T. WOOD, OF PROVIDENCE, RHODE ISLAND, ASSIGNOR TO FRANKLIN PROCESS COMPANY, OF PROVIDENCE, RHODE ISLAND, A CORPORATION OF RHODE ISLAND.

MACHINE FOR CUTTING STRIPS OF MATERIAL INTO PREDETERMINED LENGTHS.

1,145,450.

Specification of Letters Patent.

Patented July 6, 1915.

Application filed March 16, 1914. Serial No. 825,009.

To all whom it may concern:

Be it known that I, JOHN T. WOOD, a citizen of the United States, residing at Providence, in the county of Providence, 5 State of Rhode Island, have invented certain new and useful Improvements in Machines for Cutting Strips of Material into Predetermined Lengths, of which the following is a specification.

10 My invention relates to improvements in machines for cutting strips of fabric or similar material into predetermined lengths, the object being to provide a simple and efficient mechanism for this purpose and 15 one capable of a wide range of adjustment for different classes of work.

My new machine is particularly adapted for severing a continuous strip of tubular fabric into relatively short lengths as required for use in various arts. For instance, 20 the usual tubular lamp-wicking, stocking web and flexible, covering sleeves are fabricated by weaving or knitting the same in continuous strips of relatively great length, 25 for the sake of economy in manufacture, and the strips are then cut up into shorter pieces as required. One particular purpose for which these short lengths of fabric sleeving are adapted is for covering cop- 30 tubes used in dyeing yarn in package form. In United States Reissue Patent No. 13,223 to F. H. Daniell, dated March 28, 1911, there is described and illustrated a cop-tube of this character consisting of an interior 35 metal framework covered by a porous sleeve of reticulated fabric. The present machine is designed particularly for cutting the tubular fabric into sleeves of the required length for this purpose, but it will be obvious 40 that it is equally well adapted for various similar purposes in different arts.

The invention is fully described in the following specification, illustrated by the accompanying drawings, in which like reference characters designate like parts.

In the drawings: Figure 1 is a front elevation of my improved cutting-off machine; Fig. 2 is an enlarged detail view of the cutting knives and mechanism for operating 50 the same; and Fig. 3 is a plan view of the same.

Referring first to Fig. 1, A designates the main frame of the machine and B is the driving-shaft supported to rotate in bearings b , b . Preferably the bearings b , b

are mounted on brackets b' , b' , secured to the side of the frame A, or they might be constructed as a part of the frame. Mounted on the outer end of the shaft B is a driving-pulley C held fast by the set-screw 60 c , and adjacent thereto is a loose pulley C' onto which the driving-belt (not here shown) is shifted when it is desired to arrest the operation of the machine. The pulley C' is held in place against the hub 65 of the pulley C by a collar c' , and two collars c^2 , c^2 abut the ends of the bearings b , b and are secured to the shaft B to prevent longitudinal displacement thereof. On the inner end of the shaft B is a bevel-pinion D 70 which meshes with a larger bevel-gear D' fast on a vertical shaft E. The shaft E rotates in bearings f , f formed on the brackets F, F which are secured to the side of the frame A, and two collars e , e abutting the 75 ends of the bearings prevent end play of the shaft. Secured to the end of the shaft E above the gear D' is a smaller bevel-gear G which meshes with a similar gear G' on a horizontal stud-shaft H. The shaft H is 80 mounted to rotate in a bearing i formed as a part of a bracket I which is fastened to the upper bearing-bracket F. Fast on the inner end of the shaft H is a crank-disk J which is connected by a link L to drive the 85 feed-wheel or drum K which feeds the material M to the cutting-off shears or knives. The feed-wheel K may be of any appropriate dimensions, both as regards its diameter and width of face, and is preferably formed with side flanges k for holding the material in position on its periphery. It is mounted on a dead-spindle or axle N which is adjustable in a slot a in the frame 90 A and is secured in position by suitable means such as the nut n screwed onto its shouldered portion n' . Secured to the inner side of the wheel K, or constructed as a part thereof, is a hub k' formed with ratchet-teeth k^2 on its periphery. Mounted free to 95 turn on the spindle N between the wheel K and frame A is a rockable arm O to which the end of the link or connecting-rod L is secured by the bolt or pin l . The opposite end of the link L is pivotally secured to a 100 stud j which is mounted on the disk J and serves as a crank-pin therefor. Preferably, the crank-pin j is adjustable in a radial slot j' in the disk J and is secured in place by a nut j^2 which binds a shoulder on the 105

110

pin against the side of the disk. Through this means the amount of throw of the crank-pin during the rotation of the disk J can be adjusted to vary the range of oscillation of the rockable arm O. The arm O carries a pawl o which is held in engagement with the teeth k^2 on the hub of the wheel K by means of a spring o'. The rotation of the crank-disk J causes the arm O to be rocked back and forth on the spindle N, and with each forward movement of the arm in the direction indicated by the arrow x , Fig. 1, the pawl o will engage the teeth k^2 to turn the wheel K in the same direction. When the arm O moves rearwardly in the opposite direction from that indicated by the arrow x , the pawl o rides back over the teeth k^2 and the inertia of the relatively heavy wheel K is sufficient to resist any tendency to turn it backwardly.

Referring now to the other views of the drawings, two brackets P, P' are fastened to the front of the frame A and are formed with a sort of platen or table R which serves as a support for the cutting-knives or shears S, S'. The top of the table R is formed with raised guides r, r running lengthwise of its sides and a central, rectangular opening r' through which the material M is adapted to feed. Let into the top of the table R is a relatively thin plate S which is held in place by suitable means, such as the rivets s, s, etc., shown in Fig. 2, and serves as the fixed knife-blade. The movable knife S' is of greater thickness than the blade S and is fitted to slide between the guides r, r on the table R, being held in place by the overlapping strips r², r² which are secured to the table by the bolts r³. The two knife-blades S, S' are made with opposite V-shaped openings which correspond to the rectangular opening r' in the table R and are beveled off to form the shear-like cutting edges s', s². As the blade S' slides across the top of the blade S the edges s', s² meet at right-angles to shear the material M. At the rearward end of the blade S' is a vertical stud or pin t riveted in place as shown in Figs. 1 and 2. Rotatably mounted on the stud t is a roll T held in place by a collar t' fastened by the set-screw t². Referring particularly to Fig. 3, a cam U is mounted on the vertical shaft E with its face u adapted to engage the periphery of the roll T. The cam U is secured rotatively with the shaft by a taper pin u' or any other suitable means. Two springs V, V are secured at their ends to a pin v projecting from the side of the frame A, see Fig. 1, while their opposite ends are fastened to pins v', v' driven into the knife-blade S'. The springs V act to withdraw the blade S' to its inoperative position as shown in Fig. 3 and to maintain the roll T bearing on the cam-face u.

Projecting from the side of the frame A above the table R is a pin w on which is pivotally mounted a double, crooked arm W, only one side of which is shown in the drawings. Rotatably mounted on a pin w' extending between the sides of the arm W is a wheel or roller X adapted to bear on the material M as it leads around the periphery of the wheel K. A similarly formed, double-sided arm W' is pivoted on the pin w' and carries at its opposite end a pin w² on which is rotatably mounted a second pressure roller X'. The outer end of the arm W carries a pin w³ to which is fastened a cord w⁴ having a weight W² suspended at its end. The weight W² acts through the arm W to apply pressure to the roller X to hold the material M against the rim of the wheel K. As the material draws up from its source of supply, not here shown, it passes through a wire guide Y which projects from the end of the frame A.

As the material M delivers from the wheel K it feeds through a funnel-shaped hopper Z which is supported on arms z pivoted on the pin w. At the bottom of the hopper Z is a cross-piece z', see Fig. 2, adapted to strike against the upturned ears z² of stop-members z³ secured on the table R by the screws r³ as shown in Fig. 3. Projecting horizontally from the collar t', which is mounted on the stud t at the end of the cutter-blade S', is a pin t² locked in the collar by a check-nut t⁴. Normally, the hopper Z hangs suspended with its cross-bar z' resting against the stop-members z³, but as the cutter-blade S' moves to the left the end of the pin t² strikes against its side and tilts it into the position illustrated by dash lines in Fig. 2.

The operation of the complete machine is as follows: The material M is led up through the guide Y and over the wheel K and by turning the wheel by hand it can be fed down under the rollers X, X' and through the hopper Z until its end hangs above the shearing-blades S, S'. When the driving-belt is shifted from the idler-pulley C' onto the driving-pulley C the shaft B will be turned to drive the train of gearing D, D', G, G' to rotate the crank-disk J. As the disk J turns, it being immaterial in which direction it is rotated, the crank-pin j will act through the connecting-rod L to oscillate the arm O. The rocking motion of the arm O is transmitted through the pawl o to feed the wheel K forward, in the direction indicated by the arrow x, Fig. 1, and the extent of this intermittent rotation of the wheel may be varied by adjusting the crank-pin j toward or away from the axis of the disk J. In this way the amount of material fed through the hopper Z during each forward movement of the wheel K is regulated in accordance with the length to be severed,

During the operation of the feeding-means the shaft E, being continuously rotated, will operate the cam U to slide the cutter-blade S' to the left to bring its sharpened edge s^2 into coöperation with the edge s' on the fixed blade S. At the end of the stroke of the blade S' the pin t^3 comes into engagement with the side of the hopper Z and tilts it into the position illustrated by the dash lines in Fig. 2. The sharpened edges of the cutter-blades S, S' now meet and sever the material with a scissors-like action. After the short length of material has been cut off from the main strip it drops through the table R into a suitable receptacle arranged beneath. As soon as the severing operation has been completed the movable cutter-blade S' starts to recede from the fixed blade S and the hopper Z drops back into its original position as shown by the full lines in Fig. 2. The operation of the crank-disk J is so timed that as the cutter-blade S' moves forward to sever the material the pawl o on the arm O is moved back across the teeth k^2 on the hub k' and the wheel K remains at rest. Then, after the material has been severed the arm O will be moved forward to turn the wheel and feed the strip M through the hopper again. Thus the feeding of the wheel K takes place intermittently after each severance of the short length of material and the machine continues to operate in this manner until the whole strip is cut up. The purpose of the auxiliary roller X' is to provide for holding the material M in place on the feed-wheel K clear to the last end of the strip. That is to say, if only the roller X were used, after the end of the strip passed thereunder there would be no means for holding the material in place for another severing operation. With the present arrangement the strip is held on the wheel K even after its end feeds almost down into the hopper Z, and in this way the machine is adapted to cut the material into short lengths without wasting the last end. By adjusting the radius of movement of the crank-pin j the turning movement of the wheel K can be regulated to feed a shorter or longer length of material to the cutter-blades as required and a still wider range of adjustment can be provided by substituting feed-wheels of different diameters. The tilting action of the hopper Z is provided in order to insure that the severed end of the main strip of material will be carried back into proper position to feed between the knives after each cutting operation. If the end of the strip were left free it would be carried up on top of the blade S as the blade S' sheared through the material, so that it would not feed down between the blades again after the withdrawal of the movable cutter. As now arranged the depending end of the strip is controlled by the hopper Z to

carry it back into position above the opening in the table R after each cutting operation.

It will be seen that my new invention provides a particularly simple and efficient means for severing a strip of material into predetermined lengths and the machine is capable of a wide range of adjustment with very slight changes in its mechanism. Being so simple in construction it is proof against derangement or getting out of order and once set the mechanism will operate automatically for long periods without any attention from the operator.

Various modifications might be made in the structure and arrangement of the parts of my new device without departing from the spirit or scope of the invention.

Therefore, without limiting myself to the precise construction shown and described, what I claim is:

1. In a machine of the class specified, the combination with a feed-wheel adapted to receive a strip of material on its periphery, of means to intermittently rotate the wheel to feed the material downwardly therefrom in predetermined lengths, horizontally disposed cutter-blades arranged below the wheel to adapt their cutting edges to act on the material as it is fed therebetween, means to operate one of the cutter-blades to periodically sever the material, guiding-means engaging the material as it delivers from the feed-wheel, and means to operate the guiding-means after each severing operation to bring the feeding end of the material into position to enter between the cutter-blades at the next feeding operation.

2. In a machine for cutting strips of material into predetermined lengths, the combination with a horizontal table provided with an aperture, of a knife-blade fixed on said table, a movable knife slidable on the table, a feed-wheel arranged above the table to adapt it to receive the material to feed the latter down through the aperture therein, means to rotate the feed-wheel at predetermined intervals, and means to reciprocate the movable knife to sever the material in lengths as the feed-wheel delivers it thereto.

3. In a machine of the class specified, the combination with a horizontal table provided with a central aperture and guides extending along its sides, of a knife-blade overfixed on the table with its cutting-edge overhanging the edge of the aperture, a movable knife arranged to slide in the guides on the table to carry its cutting-edge across the edge of the fixed blade, means for reciprocating the movable knife, a feed-wheel arranged above the table to adapt it to receive the material on its periphery and feed the same down through the aperture between the edges of the knives, and means for ro-

tating the feed-wheel at intervals to deliver the material to the knives in predetermined lengths.

4. In a machine of the class specified, the combination with a main frame, of a horizontal, apertured table overhanging the side of the frame, a cutter-blade fixedly mounted on said table over the aperture therein, a movable cutter-blade slidable on the table across the face of the fixed blade, a cam for operating the slidable cutter-blade, power-actuated means for operating the cam, a feed-wheel mounted in bearings on the frame above the table to adapt it to receive a strip of material to feed it downward through the aperture between the cutter-blades, and means to rotate said feed-wheel at intervals to deliver the material to the cutter-blades in predetermined lengths.
5. In a machine of the class specified, the combination of a fixed cutter-blade formed with a sharpened cutting-edge, of a movable blade having a similar cutting-edge and adapted to slide across the face of the fixed blade, a roll on the movable blade, a cam engaging the roll to slide the blade, and means to feed a strip of material between the blades at regular intervals to cause the same to be severed into predetermined lengths.
6. In a machine of the class specified, the combination with a fixed cutter-blade, of a movable blade adapted to slide across the face of the fixed blade, a rotating cam for operating the movable blade, resilient means for retracting the movable blade to its in-

operative position, and means to intermittently feed a strip of material between the blades when the latter are open to cause the same to be operated upon at regular intervals to sever it into predetermined lengths.

7. In a machine of the class specified, the combination with cutter-blades formed with shearing-edges, of means to cause a relative reciprocation between the blades, means to intermittently feed a strip of material between the shearing-edges of the blades, guiding means engaging the sheared end of the strip to bring it into position to enter between the blades during the feeding operation, and means to operate said guiding-means after each shearing action of the cutter-blades.

8. In a machine of the class specified, the combination with a wheel adapted to receive a strip of material on its periphery, means to intermittently rotate the wheel to feed the material in predetermined lengths, severing-means for cutting the material as it feeds therethrough, a hopper through which the material feeds as it leads from the wheel, and means to actuate said hopper during the operation of the severing-means to bring the severed end of the material into proper position to feed through the severing-means.

In testimony whereof I affix my signature in presence of two witnesses.

JOHN T. WOOD.
